METAL HEEL

Albert von Hayn, Bad Homburg von der Höhe,
Hesse-Nassau, GermanyApplication September 8, 1934, Serial No. 743,200
In France January 3, 1934

9 Claims. (Cl. 36—40)

The invention refers to a metal heel which is hollow and which, in place of the usual heels made of leather or wood, may be fitted to any kind of footwear.

According to the invention the heel can be made in any form, dimension and execution desired, thus making it suitable for ladies' and gentlemen's footwear, as well as for military and sports boots or any other line. It is, however, more particularly intended for ladies' shoes.

Not only does it advantageously contrast with the usual heels of leather or wood, but also with the metal heels known up to now. Compared with the leather- and wood-heels it offers the advantage of greater firmness and constancy, as well as absolute unchangeableness. This is first of all noticeable in its appearance, being unaffected by humidity and notwithstanding any ordinary mechanical strain. More especially this enters into account if, as provided by this invention, the surface of the metal heel, instead of being covered with a lacquer- or colour-coating, as customary up to now, undergoes a treatment resulting in a practically unchangeable and indissoluble colouring or metallization. In consequence of its hollow construction the heel, according to the invention, is furthermore appreciably lighter in weight than the usual leather- or wood-heels, particularly if produced of light metal.

Attempts have been made to produce metal heels with the object of fitting them to ladies' footwear principally, but those metal heels could not make headway for two reasons: on the one hand the visible surfaces of the heel could not be made to have a pleasant and really durable appearance, and on the other hand the fixing of the heels to the shoe became rather expensive and difficult, so much so, that for a manufacturing concern it became practically impossible to be carried through. These two disadvantages are absolutely obviated by the heel forming the object of the present invention. By very simple means the fixing can be effected to last, the heel is light in weight and yet thoroughly stable, the outward surfaces are resistant to a high degree and in appearance they not only come up to the known kinds of heels, but surpass them even by far.

The heel according to the invention thus justifies all claims that may be put forward for a really useful metal heel, especially for ladies' foot-wear.

The one part of the problem, the question of the inside equipment and the fixing is solved by a number of small tubes being provided inside the

hollow heel, that reach from the lower end of the heel, say about from the treading base, straight or sloping up to a point, where the heel touches the fitting base of the shoe, e. g. the inner sole. These small tubes may be formed to become one piece with the heel body, more especially if the heel is produced by the "squirt-casting" process, or else these tubes may be formed as parts of a fitting to be inserted into the hollow heel.

Through the said small tubes fixing pins corresponding in length are passed from below right through the sole of the shoe, where they are bent and securely flattened by say riveting them down.

At the lower end of the heel a treading pad of leather, rubber or the like, is suitably fastened, interchangeable at will. In order to be able to fix that treading pad in the usual way, at the lower end of the metal heel a piece of leather or the like is inserted, so as to serve as bed or prop for the treading pad. It has proved suitable to unite the said inserted bed or prop with the heel by means of the aforesaid fixing pins. This is effected by passing these pins through the inserted bed or prop, which preferably has previously been provided with suitable holes.

To increase their stability and at the same time that of the heel as a whole, the said tubes can be joined to one another or else united with the inner wall of the heel by ribs or studs. For the production of the small tubes by the casting process or rather to ameliorate the forming process it may be advisable to slit the small guiding tubes at the side a trifle less than the width of their inner diameter or the diameter of the fixing pins respectively, so that the pin like parts of the body of the form, which during the casting have to keep the inner space of the small tubes open, are connected by a support with the other parts of the body of the form, whereby the exact position of the small tubes is practically secured. Furthermore with that execution the walls of the small tubes may yield somewhat, in case the fixing pins should at one time be chosen slightly thicker than the bore of the small tubes.

The exterior of the heel is, by means of an electro-galvanic process, covered with an insoluble coating, either metallic or otherwise, in one or several colours. The most suitable process for that purpose is known by the name of "Eluxation process".

It goes without saying that the outer surface of the heel must not necessarily be perfectly smooth. It may for technical reasons be sup-

plied also with indentations or projections e. g. for ski boots, or else with plastic ornamentations. With special kinds of ladies' shoes it is customary to cover the heel front with an elongation of the treading sole. In order to make this also possible for metal heels of the invention, a corresponding indentation at the heel front may be made with dovetail like chamfered rims preferably, into which the said leather strip may 10 be cemented.

Further details and advantages of the invention will be evident from the following description.

Some examples of execution of the invention 15 are shown in the annexed drawings.

Fig. 1 shows a high heel as well as the neighbouring part of the ladies' shoe in vertical section (on the line 1—1 of Fig. 3) and at the same time means for securing the heel to the shoe.

20 Fig. 2 shows the bottom end of the heel as seen from below.

Fig. 3 shows the heel itself as seen from above.

Fig. 4 shows a ladies' heel of half height in vertical section.

25 Fig. 5 shows the top plan of a gentleman's heel.

Fig. 6 shows the vertical section relating thereto on the line 6—6 of Fig. 5.

Fig. 7 is a view similar to Fig. 3 but showing an execution with the small tubes open at the 30 side.

Fig. 8 shows a section of a ladies' heel, in which the fixing tubes form part of a constituent or fitting of its own.

35 Fig. 9 shows this constituent alone as seen from the side,

Fig. 10 the same in front view, and

Fig. 11 the same as seen from below.

According to Figs. 1 and 3 the heel consists of a thin walled metal body 1, preferably produced by the squirt casting process, which with its upper edge 2 joins the fixing base 3 of the shoe. At a slight distance from the bottom end 4 of the heel a bottom level 5 is fitted. From this level up to the height of edge 2 or rather up 45 to where the respective parts of the heel are meant to lean against the fixing level of the shoe, ribs 6 are fitted, that on their inner border contain obliquely upwardly running channels 6' which are continued downwardly through 50 the bottom level or partition 5. In the indentation or recess that remains between the bottom level 5 and the border 4 I locate an insert or filling piece 15 having four openings that correspond with the mouths of the channels 6' in level 5.

55 The heel is provided with a vaulting passing to the joint of the shoe which, if needs be, may at 7 have an elongation for support of the arch.

The front of the heel may according to Fig. 2 be supplied with an indentation, recess or groove 60 bounded by dovetail like chamfered rims 9' in which a leather strip or an extension of the treading sole 9 may be cemented when finishing the shoe.

65 By way of example the fixing of the heel can be effected as follows. Once the heel is brought into the required position relating to the shoe, correspondingly long measured pins 10 are driven through the openings of the insert 15 and through the channels 6'. This is suitably effected by a pressure tool 21. A metal last 19 which at suitable points 16 is rounded off, serves to turn the points of the pins 10. These bent ends 70 14 may, if need be, be pressed flat by special stamps 20, 20' as shown in Fig. 1.

75 On the insert 15 a treading pad 18 of one or

several parts can now be fixed in the usual way, i. e. by pins 17' as shown in Figs. 4 and 6.

Fig. 4 requires no further explanation. The details are here correspondingly the same as in the example Figs. 1—3. The only difference is 5 that Fig. 4 shows the ends 12 of the pins 10 as still in the straight condition. It is understood that the heads 17 of the pins 10 are pressed so deep into the insert 15 that a flat level results for fixing the treading pad.

10 The gentleman's heel according to Figs. 5 and 6 differs in its construction from the aforementioned examples essentially in so far only, that the small tubes 25 are all connected with each other by ribs 27. Consequently the bottom level 15 5 is not required, since the inserted piece 15 gets sufficient support at the lower borders of these ribs. In this example the small tubes 25 may all be arranged perpendicularly to the ground level.

20 Fig. 7 differs from Fig. 3 substantially only by the channels 6' being open at one side, as indicated above.

25 In the example of execution as per Figs. 8—11 the small tubes 6'' together with a plate 13 25 joining them among themselves form an independent constituent or fitting of the heel. The heel 1 is therefore in this case a simple thin walled hollow body. Independent of the arrangement of the said small tubes set the heel 30 body can be provided with stiffening ribs.

35 It is not absolutely necessary that the connecting plate 13 be fitted to the bottom end of the small tubes 6''. It can also be fitted elsewhere e. g. at the top end. In the latter case it may be made of such a size, as to close like a lid covering or sealing the hollow space of the heel. In this embodiment it will be advisable to allow the bottom ends of the small tubes to protrude into the respective openings of the level 40 5 so that an exact fit of the small tubes-set during the fixing process is warranted.

45 The outer surface 8 of the heel is either ornamented according to wish or, as indicated, preferably galvanically coloured ("eluxed") or metallized.

I claim as my invention:

1. A heel for footwear of all kinds, consisting of a hollow body having a thin wall surrounding an inner space, a supporting structure within said inner space and separated from said wall, said supporting structure comprising a plurality of guide channel members adapted to having heel attaching pins passed therethrough and reaching from about the ground level of the heel to where the heel comes into contact with the shoe, and means for retaining said guide channel members in their spaced positions.

2. A metal heel for footwear of all kinds consisting of a hollow body having a thin wall surrounding an inner space, tubular guides for pins or nails, said guides being arranged within said inner space and reaching from about the ground level of the heel to where the heel comes into contact with the shoe, and means located within 60 said inner space, for connecting said guides with each other.

3. A metal heel for footwear of all kinds, comprising in combination a hollow thin-walled body, in said body a bottom level provided with holes 70 and a set of small tubes forming an independent constituent loosely inserted into the hollow space of the body and being of suitable length and arrangement for reaching from the holes provided in the bottom level of the heel body to 75

where the heel comes into contact with the shoe.

4. A metal heel for footwear of all kinds, consisting of a hollow thin-walled body, in the inner space of which relatively thin guide channel members are provided, that reach from about the ground level of the heel to where the heel comes into contact with the shoe, an indentation being provided at the bottom of the heel for receiving a filling piece, that has holes corresponding with 10 the end points of the said guide channel members when inserted.

5. A metal heel for footwear of all kinds, consisting of a hollow thin-walled body, in the inner space of which relatively thin guide channel members are arranged, that reach from about the ground level of the heel to where it comes into contact with the shoe, a dovetail like indentation being provided at the front of the heel for receiving a strip of sole leather as a covering.

20 6. A metal heel for footwear of all kinds, consisting of a hollow body having a thin wall surrounding an inner space, a supporting structure within said inner space and separated from said wall, said supporting structure comprising a plurality of guide channel members adapted to having heel attaching pins passed therethrough and reaching from about the ground level of the heel to where the heel comes into contact with the shoe, and means for retaining said guide 25 channel members in their spaced positions, said heel being provided with an elongation protruding from the upper end of the heel front and being suitably shaped for the purpose of supporting the joint of the shoe.

30 35 7. A shoe having a hollow heel of thin metal,

the walls of which heel surround an inner space, a supporting structure within said inner space and separated from said wall, said supporting structure comprising a plurality of guide channel members adapted to have heel attaching pins 5 passed therethrough and reaching from about the ground level of the heel to where the heel comes into contact with the shoe, and attaching pins passed through said guide channel members, the upper ends of said pins projecting upwardly from said guide channel members through the sole of the shoe and then downwardly again through said sole.

8. A heel for footwear, consisting of a hollow body the wall of which surrounds an inner space, 15 said body being provided with a transverse partition at a distance from its lower edge so as to form a recess at the bottom of said body, and upright guides having channels for receiving pins or nails, said guides being arranged circumferentially 20 within said inner space and extending upwardly from said partition, the latter having openings in line with said guides.

9. A heel for footwear, consisting of a hollow body the wall of which surrounds an inner space, 25 said body being provided with a transverse partition at a distance from its lower edge so as to form a recess at the bottom of said body, guide channel members for receiving pins or nails, said members being arranged circumferentially with- 30 in said inner space and extending upwardly from said partition, said members and said partition being integral, and a filling piece disposed in the recess below said partition.

ALBERT VON HAÝN. 35
